UNITED STATES PATENT OFFICE.

JOHN EDWARD ROBERTS, OF ONEDIA, KENTUCKY.

LOCOMOTIVE-ENGINE.

SPECIFICATION forming part of Letters Patent No. 716,107, dated December 16, 1902.

Application filed September 13, 1901. Serial No. 75,287. (No model.)

To all whom it may concern:

Be it known that I, JOHN EDWARD ROBERTS, a citizen of the United States, residing at One-dia, in the county of Clay and State of Kentucky, have invented new and useful Improvements in Locomotive-Engines, of which the following is a specification.

This invention relates to locomotive-engines and is in the nature of an improvement upon the construction illustrated and described in a former patent granted to me June 6, 1899, No. 626,566.

The invention relates particularly to locomotive-engines of the double-acting type, the objects of the invention being to equalize the power of a locomotive at each side of the same and at the same time provide means whereby dead-centers are effectually overcome and the accidental slipping of the driving-wheels on the rails obviated.

The invention also has the advantage of overcoming to a large degree the wear and tear on the road-beds, and thereby renders travel over such road-beds safer.

With the above general objects in view the invention consists in a locomotive-engine embodying certain novel features and details of construction and arrangement of parts, as hereinafter fully described, illustrated, and claimed.

In the accompanying drawings, Figure 1 is a plan view of a sufficient portion of a locomotive-engine to illustrate the application of the present improvement thereto, said view showing the cylinders in section. Fig. 2 is a side elevation of the driving-wheels at one side of the engine, showing the manner of associating the connecting-rod, crank-levers, cranks, and pitmen therewith. Fig. 3 is a similar view showing the same connections at the opposite side of the engine. Fig. 4 is a side elevation of one of the driving-wheels. Fig. 5 is a diametrical section through the same. Fig. 6 is a side elevation of another one of the driving-wheels. Fig. 7 is a diametrical section therethrough. Fig. 8 is a side elevation of one of the crank-disks. Fig. 9 is a diametrical section through the same.

Like numerals of reference denote like parts in all the figures of the drawings.

Referring to the drawings, and particularly to Figs. 1, 2, and 3 thereof, 1, 2, 3, and 4 repre-

sent four cylinders arranged in pairs, one pair at each side of the locomotive. The front driving-wheels (indicated at 5) are mounted upon the axle 6 and the rear driving-wheels (indicated at 7) upon the rear driving-axle 8.

9, 10, 11, and 12 represent pistons of ordinary construction working, respectively, in the cylinders 1, 2, 3, and 4.

Connected with the pistons 9, 10, 11, and 12, respectively, are piston-rods 13, 14, 15, and 16, which are mounted in suitable stuffing-boxes in the rear ends of the cylinders, the said piston-rods being respectively connected with the forward ends of pitmen 17, 18, 19, and 20. The connecting-rods 17 and 20, which are actuated by the pistons in the outer cylinders 1 and 4, are connected to wrist-pins on crank-disks fast on the outer opposite ends of the rear driving-axle 8, while the rods 18 and 19 are connected to the ends of crank-levers on the front driving-axle 6. The cranks are so disposed with relation to each other that the four pistons will always be half a stroke apart, as illustrated in Fig. 1, so that as the two pistons on one side are moving in one direction those on the other side will be moving in the opposite direction. By an examination of Fig. 1 of the drawings it will be seen that during a portion of the revolution of the driving-wheels the two pistons at one side of the engine will be moving in the same direction, and this movement will continue a distance equal to one-half the stroke of any one piston, while during the next half-stroke one of the pistons will be moving in one direction and the other piston on the same side of the engine will be moving in the opposite direction. The arrangement is such that the two pistons at one side of the engine will always pass each other when the cranks of the driving-wheels are at an angle of forty-five degrees relatively to each other. The same movement takes place with respect to the other two pistons on the opposite side of the engine, and thus there will always be four pistons acted upon by the steam at the same time—two on each side of the locomotive. This is productive of equal power on each side of the locomotive and avoids the possibility of dead-centers. It also distributes or equalizes the strain produced by the frame and by the body of the locomotive

on the rails of the road-bed in starting a heavy train of cars, and thus prolongs the life of the road-bed and the life of the locomotive-engine.

5 Each of the front driving-wheels is provided in its outer side with a diametrically-disposed recess 35, in which is arranged a crank-lever 36, which is inlaid about flush with the outer surface of the wheel, as illustrated in Fig. 5. The crank-lever 36 has a central opening at a point midway between its ends to receive the axle and is provided at one extremity with a wrist-pin 37 to receive the overlapping ends of the adjacent connecting-rod or pitman, while its opposite end is formed with an opening to receive a fastener in the form of a bolt or screw 38 for connecting said end of the crank-lever to the wheel. The object of this arrangement is best illustrated in Fig. 2, in which it will be observed that the rearward thrust imparted to the pitman 19 is transferred by the crank-lever to the upper portion of the wheel above its axis of rotation, where the power to propel or turn the 20 wheel is much more effective. This principle is well recognized by those familiar with the art to which this invention appertains. The rear driving-wheels are provided in their outer surfaces with recesses 39, in which are placed 25 cranks 40, each crank being provided at one end with an opening 41 for the reception of the axle and at its opposite end with a wrist-pin 42 to receive the rear end of one of the connecting-rods 21. The crank 40 is what is 30 usually known as a "double" crank and arranged with one arm 40 lying in the recess 39 of the adjacent rear driving-wheel, while the other arm of the crank is secured to the inner side of a crank-disk 43, as shown in Fig. 35 1 and indicated by dotted lines in Fig. 2.

The crank-disk is provided with openings 44, arranged at a quarter of a revolution apart, one of said openings being designed to receive a pin on the crank 40, while the other opening receives the wrist-pin 45, by means of which the rear end of the connecting-rod or pitman 20 or 17, as the case may be, is connected to said wheel.

From the foregoing description it will be 50 apparent that I have effectually overcome dead-centers in the locomotive-engine by arranging the driving cranks and pistons in such manner that two or four of the pistons will be simultaneously acted upon by the 55 steam within the cylinders; further, that the back thrust of the pitmen will be transferred and reversed by the crank-levers and applied in a forward direction to the wheels above their axes of rotation. In this way greater 60 power is obtained or the same amount of power obtained with a less expenditure of steam, and by providing a pair of cylinders at each

side of the locomotive the cylinders may be materially reduced in size as compared with the single-cylinder engines at present in use 65 without sacrificing power.

Any preferred form of valve mechanism may be employed for operating the pistons under the arrangement shown in Fig. 1 and the valve-controlling mechanism will be of 70 such construction as to enable the two inside cylinders to be operated independently of the outside cylinders, or vice versa. Also any form of reverse mechanism may be employed for reversing the direction of rotation of the 75 driving-cylinders of the engine. All of such means will be under the control of the engineer.

It will be understood that the invention is susceptible of various changes in the form, 80 proportion, and the minor details of construction, and I therefore reserve the right to make such changes as properly fall within the scope of the appended claims.

Having thus described the invention, what 85 is claimed, and desired to be secured by Letters Patent, is—

1. In a locomotive-engine, the combination with the front and rear driving-wheels thereof having diametrically-disposed recesses, of levers arranged in said recesses and provided with wrist-pins, pitmen carried by the wrist-pins to connect the front and rear driving-wheels, crank-disks mounted upon the wrist-pins of the rear driving-wheels, a pair of cylinders arranged at each side of the locomotive, a piston working in each cylinder, and pitmen connecting the wrist-pins of the front drive-wheels and the disks to the piston-rods, whereby the pistons in each pair of cylinders 100 are located at a distance apart equal to one-half of a complete stroke in either direction to cause the pistons at one side of the engine to move in the same direction for one-half the stroke of any one piston while during the 105 next half-stroke the piston will move in opposite directions.

2. In a locomotive, the combination with the front and rear driving-wheels thereof having diametrically-disposed recesses, of levers 110 arranged in said recesses and provided with wrist-pins, pitmen carried by the wrist-pins to connect the front and rear driving-wheels, crank-disks mounted upon the wrist-pins of the rear driving-wheels, cylinders, and pitmen connecting the wrist-pins of the front drive-wheels and the disks to the piston-rods. 115

In testimony whereof I affix my signature in presence of two witnesses.

JOHN EDWARD ROBERTS.
